UNITED STATES PATENT OFFICE.

CHARLES M. JARVIS, OF BERLIN, CONNECTICUT, ASSIGNOR TO THE BERLIN IRON BRIDGE COMPANY, OF SAME PLACE.

DESIGN FOR A CLEVIS.

SPECIFICATION forming part of Design No. 27,469, dated August 3, 1897.

Application filed June 22, 1897. Serial No. 641,837. Term of patent 14 years.

To all whom it may concern:

Be it known that I, CHARLES M. JARVIS, a citizen of the United States, residing at Berlin, in the county of Hartford and State of Connecticut, have invented and produced a new and original Design for a Clevis, of which the following is a specification, reference being had to the accompanying drawings.

Figure 1 is a side view of a clevis, showing my design. Fig. 2 is an edge view of the same, and Fig. 3 is a transverse section thereof on the line *x x*.

As shown in the drawings, the leading or material feature of my design consists of the rounded bead or enlargement on the outer side of each strap at its junction with the eye or head. The straps 4 at their outer ends have a contour in side view which may be

called "balloon-shaped," as shown in Fig. 1, with a round hole 5 in the central portion. 20 The straps 4 widen with curved outer edges, which meet the sides of the head 6. From near the smaller end of the balloon-shaped portion of the straps there is a bead or enlargement 7, which widens from its end 8 toward the head 5, as shown, giving the clevis 25 an oval form in cross-section.

Having described my invention, what I claim as new, and desire to secure by Letters Patent, is—

The design for a clevis as herein shown and described.

CHAS. M. JARVIS.
